US00D660530S

(12) **United States Design Patent**
Geringer et al.

(10) **Patent No.:** **US D660,530 S**
(45) **Date of Patent:** **** May 22, 2012**

(54) **ROBOT VACUUM CLEANER**

(75) Inventors: **Joseph Geringer**, Merrimack, NH (US);
Richard Watson, Norwell, MA (US);
Jason Cooper, Watertown, MA (US)

(73) Assignee: **iRobot Corporation**, Bedford, MA (US)

(**) Term: **14 Years**

(21) Appl. No.: **29/382,285**

(22) Filed: **Dec. 30, 2010**

(51) LOC (9) Cl. **15-05**

(52) U.S. Cl. **D32/21**

(58) Field of Classification Search **D32/21, D32/31; 701/25, 23, 200; 15/319, 307, 347, 15/4, 340.11, 46; 901/1, 46; 700/25; 318/568.12, 318/568.16**

(57) **CLAIM**

The ornamental design for a robot vacuum cleaner, as shown and described.

DESCRIPTION

FIG. 1. is a perspective view of the robot vacuum cleaner.

FIG. 2 is a rear view thereof.

FIG. 3 is a front view thereof.

FIG. 4 is a right side view thereof.

FIG. 5 is a left side view thereof.

FIG. 6 is a top view thereof; and,

FIG. 7 is a bottom view thereof.
